UNITED STATES PATENT OFFICE.

CARL L. JAEGER, OF MAHWAH, NEW JERSEY.

RECORDING DEVICE.

1,106,944.

Specification of Letters Patent. Patented Aug. 11, 1914.

Application filed September 24, 1912. Serial No. 722,060.

To all whom it may concern:

Be it known that I, CARL L. JAEGER, a citizen of the United States, and a resident of Mahwah, in the county of Bergen and 5 State of New Jersey, have invented certain new and useful Improvements in Recording Devices, of which the following is a specification:

The invention relates to recording apparatus, and more particularly to apparatus of this character in which the record is effected through suitable printing means adapted to make an impression upon a record sheet only at predetermined periods.

10 One of the objects of the invention is to provide means for recording the apparent movement of the needle of a compass carried by a ship or other traveling object, and thereby provide a record of the course of 20 the same.

The invention contemplates, furthermore, a disengagement of the member, having the real or apparent movement, from its support during the printing operation and a 25 printing by said member; and, moreover, simultaneous change of further printing means during such disengagement. The disengagement is arranged, furthermore, to take place in such a manner that the member will be properly returned to its normal 30 position after printing.

The nature of the invention will best be understood when described in connection with the accompanying drawings, in 35 which—

Figure 1 is a vertical section through a recording compass, as one embodiment of my invention. Fig. 2 is a plan thereof. Fig. 3 is a vertical section of a similar apparatus, 40 and illustrates a modification therein. Fig. 4 is a plan thereof. Fig. 5 is a transverse section taken on the line 5—5, Fig. 3. Fig. 6 is a plan of a portion of the record strip, on an enlarged scale, with a record printed 45 thereon. Fig. 7 is a detail, fragmentary view illustrating the adjustment of the “lubber’s line”.

Similar characters of reference designate corresponding parts throughout the several 50 views.

Referring to Fig. 1 of the drawings, 20 designates a suitable casing within which is swung on suitable gimbal journals 21 and 22, the compass casing 23. A transverse plate 55 24 is secured thereto, and to this is centrally

secured the pivot 25 for the compass needle 26 which carries the usual compass card 27 and an additional printing annulus 28 corresponding to the points of the compass. The card and printing annulus may, of course, be one. The characters on this annulus may be formed in any desired manner; but I have shown the same, for the purpose of reducing the weight of the card, as small points raised from the surface of a thin strip of light metal, such as aluminum. Above this card and over a small segment thereof is the record tape 29 which is taken from a reel 30, preferably outside the casing 20, and is brought through an opening 31 in the casing 23, then over the said compass card and between said card and an inking pad or ribbon 32 secured to the transparent cover of casing 23 and adapted to coöperate with the aforesaid segment of the said card. 60 70 75

The record tape, after passing over suitable rollers and advancing mechanism herein-after more fully set forth, passes out through suitable openings in the two casings 20 and 23 where it may be received in any suitable manner. 80

To effect the printing operation, the entire compass card and needle together with the printing annulus are arranged to be raised off the pivot 25, and the segment co-operating with the record strip is brought into contact with said strip, forcing the same against the inking pad 32. The disengagement of the card and needle is effected by means of a platen 35 mounted about the 90 pivot 25 and provided with a rim 36 adapted to fit under the printing annulus 28 and about a downwardly directed flange 39 of the compass card. This securely positions the said card and insures its proper return 95 when the platen 35 is depressed.

To raise the platen 35, a piston 40 working in a cylinder 41 is connected thereto through piston rod 42, plate 43 and rods 44. Fluid under pressure or vacuum is arranged to be 100 supplied to the said piston 40 at predetermined intervals; and is led into the cylinder 41 through a suitable hose connection 45 which passes through the gimbal journals to the outside of the casing 20. The fluid employed for the purpose of operating the piston 40 is derived from any suitable source (not shown); and its delivery to its cylinder 41 is controlled by a suitable clock 51, which clock is designed to rotate a valve piece 52 110

provided with a suitable duct 53 through which communication may be afforded to the hose connection.

As the platen 35 is raised, an arm 55 secured to the plate 43 moves upwardly therewith and engages one end of a lever 56 fulcrumed to the casing 23, and whose other arm carries a suitable pawl 58 engaging the teeth of a ratchet wheel 59 of a roller 60, between which and a roller 61 the record strip 29 is passed and advanced through the movement of the ratchet wheel as the platen 35 returns from its raised position; thus advancing a fresh portion of the record strip 15 into the position to be printed upon. On the upward movement, the pawl slips by the teeth of the ratchet wheel. A vent 65 is provided in the cylinder 41 to relieve the pressure within said cylinder when the fluid 20 supply is shut off, and permits the return of platen 35 and thereby the compass card with its needle, which readily return under their own weight, the flange 39 insuring the centering of the said compass card and needle.

Referring to Figs. 3, 4 and 5, a modification in the manner of operating the printing elements is shown. In this embodiment, the compass card 27 and needle 26 are mounted as before upon the pivot 25 which is carried 30 in this instance by a movable plate or bar 70, the said bar being secured to oppositely disposed vertical tubes 71 and adapted to move therewith. A cross-bar 72 is secured to the upper ends of these tubes and carries at 35 right angles thereto a platen 50 and is provided, also, with a downward projection 73 in the axis of the pivot 25, the said projection terminating a slight distance above the needle bearing 74 to insure against displacement of the compass card and needle. The lower ends of the tubes 71 are fitted about 40 corresponding vertical guide rods 75 fixed to the compass casing 23. A plate 76 connects the lower ends of these tubes, and coiled 45 springs 77 about the rods 75 act against this plate to normally hold the compass needle and card in the normal raised position.

A plate 78 is secured to the compass casting 23 near the bottom thereof and above the 50 plate 76; and from this plate extends downwardly a cylinder 79 having therein a piston 80 bearing against the plate 76. When fluid under pressure is introduced into the cylinder 79, the piston is advanced and thereby 55 depresses the tubes 71 and with them the compass card and needle toward the printing wheel 82 and record strip 83 over which is transversely directed an inking ribbon 84. The printing annulus of this card as well as 60 the time wheels and other printing devices then make their various impressions upon the record strip. The tape in this embodiment is preferably taken from a reel 85 mounted within the compass casing 23; and 65 the fluid to operate the piston 80 is con-

trolled as in the previously described embodiment through the time actuated valve 52. The motion of the time wheels and other wheels to change the indication of the same and of the inking ribbon to present a fresh surface, is derived from the movement of the plate 76 through suitable intermediate mechanism. The printing tape may be variously located with respect to the type, or ink may be applied directly to the type.

For the sake of simplicity, I have merely disclosed the printing of the course 90, Fig. 6, the time 91 and the "lubber's line" 92. It is understood, however, that various other records may be printed on the strip 29 by providing the necessary printing wheels, which may be set by hand or otherwise controlled, as is well understood. The printing of the "lubber's line" 92 is effected by a pivoted type member 93 supported in an adjustable carriage 94 secured to the inner wall of casing 23 and adjusted by means of the graduated head 95. As the compass card is moved upwardly, in the embodiments disclosed in Figs. 1 and 2, the type member 93 bearing the "lubber's line" is moved upwardly and thereby into contact with the strip 29 and forces the same against the ink pad 32 to print the record of the "lubber's line".

I claim:—

1. A recording device, comprising: a movable member, and means to support the same; printing means controlled by said movable member; a record sheet, and means to advance the same with respect to the movable member; suitable platens; and means to effect an additional relative movement between the said record sheet and the said printing means in a direction to bring the same and said platens together to print a record and to disengage the movable member from its support during the printing period.

2. A recording device, comprising: a movable member, and means to support the same; printing means carried by said movable member; a record sheet, and means to advance the same with respect to said movable member; suitable means to effect an additional relative movement between the said record sheet and the said printing means in a direction to bring the same and said platens together to print a record and to disengage the movable member from its support during the printing period.

3. A recording compass, comprising: a magnetic needle, and means to support the same; printing means carried by said compass needle; a record sheet, and means to advance the same with respect to said compass needle; suitable platens; means to effect a relative movement between the said record sheet and the said printing means carried by the compass needle in a direction to bring

the same and said platens together to print a record and to disengage said needle from its support during the printing period.

4. A recording compass, comprising: a magnetic needle, and means to support the same; a printing annulus carried by said compass needle, and suitable projections thereon to designate the corresponding points of the compass; a record sheet, and means to advance the same with respect to said printing annulus; means to effect a relative movement between the said record sheet and the said printing annulus carried by the compass needle in a direction to bring the same and said platens together to print a record and to disengage said needle from its support during the printing period.

5. A recording device, comprising: a movable member, and means to support the same; printing means controlled by said movable member; a record sheet, and means to advance the same with respect to the movable member; suitable platens; means to effect an additional relative movement between the said record sheet and the said printing means in a direction to bring the same and said platens together to print a record and to disengage the movable member from its support during the printing period; and additional printing means set by the relative movement between the record sheet and the said former printing means.

6. A recording device, comprising: a movable member, and means to support the same controlled by said movable member; printing means; a record sheet, and means to advance the same with respect to the movable

member; suitable platens; means to effect a relative movement between the said record sheet and the said printing means in a direction to bring the same and said platens together to print a record and to disengage the movable member from its support during the printing period; fluid pressure means to control the movement of the means effecting the printing; a time operated device controlling the admission of fluid to the fluid pressure means; and advancing means for said record sheet and actuated by said fluid pressure means.

7. A recording device, comprising: a movable member, and means to support the same; printing means carried by said movable member; suitable platens; a record sheet; a cylinder, and a piston therein; means to admit fluid under pressure behind said piston; means normally disengaged from said movable member to lift same off its support and to bring the printing means carried thereby into contact with the record sheet and between said platens to print a record thereon; means connecting said piston with said lifting means; advancing means for said record sheet; and means connecting said piston with said advancing means.

Signed at Suffern, in the county of Rockland, and State of New York, this 17th day of September, A. D. 1912.
